ROLLER LEVELER MACHINE

Eric Birger Fernberg, Edgware, England, assignor
to The Edward G. Budd Manufacturing Company,
Philadelphia, Pa., a corporation of Pennsylvania

Application April 3, 1934, Serial No. 718,754
In Great Britain April 28, 1933

7 Claims. (CL 153—54)

This invention relates to a machine employed in the sheet metal industry and known generally as a roller leveler machine for the cold working of metal sheets.

5 It is essential, in the treatment of metal sheets which are to be used ultimately in deep drawing and complex forming operations, to eliminate as far as possible what are known as stretcher strains, and this has been achieved by passing the 10 sheets individually through a roller leveler machine in which they are subjected to a bending and subsequent straightening operation.

Machines for this purpose have been proposed and used with success, although they have not 15 attained all the desiderata thought to be necessary in the cold working of metal sheets. Such machines comprise a series of rolls through which the sheets are passed after being subjected to a bending operation over a roll which is caused to 20 move automatically out of the plane of the straightening rolls either by electrical means, controlled through the body of the sheets or by pneumatic means operable when the sheet is first gripped by the pinch or leading rolls.

25 Machines of this type are described in the prior U. S. Patents Nos. 1,649,704; 1,649,705 and 1,649,706, all dated November 15, 1927 and 1,855,709, dated April 26, 1932.

In order to obtain the most satisfactory results, in which the sheets so cold-worked may be drawn and formed with facility and without wrinkling and other defects, it is desirable to produce a sharp bend and to effect the bending operation rapidly. The former of these is governed by the diameter of the rolls and the latter by the surface speed of the rolls, and both of these characteristics are in turn governed, in the existing machines, by the mechanical design. If the diameter of, or the surface speed of, the 40 rolls be decreased or increased respectively or if both be changed in the desired direction there will be a tendency of the rolls to whip. This must be avoided.

Now it is the object of the present invention to 45 provide a machine in which both of these desirable characteristics, viz. reduction of diameter of the rolls and increased surface speed are attained without any disadvantages.

50 Accordingly there is provided, in a machine of this kind, bending elements for the metal sheets in which the bend is sharper and the operation more rapid than heretofore.

The bending elements may comprise two or 55 more series of roller or ball-bearings mounted in

a plurality of bearing blocks carried by opposed and staggered beams, the one fixed and the other movable under the control of the sheet in any well-known manner.

Preferably the roller or ball bearings are arranged close together so that their peripheries present, as nearly as possible, a continuous cylindrical surface.

On account of the avoidance of whip of the beams, it is possible to increase their length and 10 thereby to treat wider sheets than has been possible hitherto, whilst with the present construction, to attain still greater rigidity, the beams may be increased in depth.

It has been proposed, in connection with the 15 treatment of wide metal sheets and in order to avoid whip of the beams, to provide extra bearings at points intermediate the ends of the beams, but this method does not give sharper bends to, nor more rapid treatment of, the sheets 20 to be worked.

As an example, will be described one form of the invention, reference being had to the accompanying drawings, Figure 1 of which is a side elevation, showing only those parts of the machine 25 pertinent to the invention. Figure 2 is a part transverse elevation of the movable element and Figure 3 a part plan view with the main straightening rollers omitted for clarity.

On a suitable base frame (not shown) is 30 mounted the roller leveler mechanism proper consisting of the upper and lower series of straightening rolls indicated at *a* and *b* between which the sheet *c* passes after being subjected to 35 the bending operation at the front of the machine.

The rolls may be driven in any well known manner.

The lower series of rolls *b* may be supported 40 in side frame members (not shown) secured to the base frame whilst the upper series *a*, arranged in staggered relation to the lower series in the direction in which the sheet *c* is fed through the machine, may be supported in a frame (not 45 shown) mounted adjustably on the base frame to permit adjustment thereof in relation to the lower series of rolls.

Towards the front of the machine are mounted a pair of pinch or draft rolls *d*, adapted to grip the 50 sheet to prevent it from slipping during the actual bending operation, which may be controlled either electrically through the body of the sheet when it is first gripped by the pinch rollers or by other means such as pneumatic or hydraulic, the 55

sheet being held further by hold-down rolls *e* at the front of the machine.

The pinch and hold-down rolls *d* and *e* are spaced apart sufficiently to allow the actual bending mechanism to be mounted and to be moved upwardly therebetween.

The bending mechanism proper comprises two transverse beams *11* and *12*, the one *12* mounted fixedly in association with the upper roll *e*, and 10 the other *11* mounted to be moved up and down in a vertical direction, between the hold-down and pinch rolls *e* and *d*, through the intermediary of the sheet, but normally being so disposed as not to interfere with the straight through 15 passage of the sheet *c* until it is gripped by the pinch rolls *d*.

Each of the transverse beams *11* and *12* carries a plurality of bearing blocks *13*, *14*, secured by 20 means of the bolts *15*, which in turn support a plurality of roller- and/or ball-bearings *16*, arranged as close to one another as possible so that their peripheries present a substantially continuous cylindrical surface. The beams *11* and *12* are arranged in opposition and in staggered 25 relation longitudinally of the machine.

The outer surfaces of the roller or ball bearings are slightly crowned, like a flat-belt pulley, as can be seen clearly in Figures 2 and 3, to avoid 30 any possibility of scoring the sheets, with the sharp edges of the bearings, as they pass through the machine.

Although the beams *11* and *12* are in staggered relationship longitudinally of the machine, it 35 must be understood that the roller- or ball-bearing elements are in transverse alignment, as will be seen in Figure 3.

A sheet to be treated is fed to the machine first through the hold-down rolls *e* and straight 40 through until it is gripped by the pinch rolls *d*, whereupon the control of the movable transverse beam *11* is actuated, in any well-known manner, to thrust the sheet upwardly and effect the bend, the sheet passing under the series of roller- and/or ball-bearings carried in the fixed transverse beam *12* thereby ensuring equal bending 45 first one way and then the other. To permit this operation the hold-down rolls *e* are allowed a small degree of slip. The sheet *c* continues on through the machine and is effectively straightened by the straightening rolls *a*, *b*.

To ensure a proper feeding of the sheet through the machine, suitable guide elements *17*, *18* may be provided.

The transverse beams *11* and *12* may be constructed of heavy section so that they will remain rigid under load and furthermore they may be increased in length and depth thereby enabling wider sheets to be treated, without introducing 55 any tendency to whip, whilst the actual bending elements, i. e. the ball- and/or roller-bearings *16* may be of much smaller diameter than is possible in the machines at present in use thereby giving greater surface speed of the bending rolls for 60 equal operating speeds, whilst in some cases the speed of operation of the machine may be increased.

In this manner the advantages of sharper bending at increased speed are attained without any 65 attendant disadvantages.

What I claim as my invention is:

1. A machine for treating metal sheets comprising spaced pairs of feeding rolls and means disposed to operate in the space between said 70 feeding rolls to stress the sheet in its passage

through the machine, said stressing means comprising two or more series of rollers and a vertically deep rigid support for each series, said series of rollers being of relatively small diameter as compared with the diameter of the feed rolls and arranged when in operative position in staggered relation transversely of the machine whereby the sheet is given a plurality of sharp bends in its passage through the machine. 5

2. A machine for treating metal sheets comprising spaced pairs of feeding rolls and means for stressing a sheet in its passage between said spaced feeding rolls, said means comprising several series of rollers arranged in staggered relation and closely spaced longitudinally of the machine, vertically deep rigid supports for said rollers extending through substantially the width of the machine, said rollers being of relatively small diameter as compared with the diameter of the feed rolls and said series being arranged 20 when in operative position in staggered relation transversely of the machine, whereby the sheet is given a plurality of relatively sharp bends in reverse direction, in its passage through the machine. 25

3. A sheet treating machine of the class described comprising spaced pairs of feeding rolls and sheet stressing means disposed to operate in the space between said pairs of feeding rolls, said stressing means comprising at least two series of rollers arranged transversely of the machine, the rollers of each series being arranged in close proximity to present a substantially continuous cylindrical periphery or surface, a fixed support for one of said series and a movable support for the other of said series, whereby the two series may be moved into staggered relation transversely of the machine to bend the sheet about both series of rollers in its passage through the machine. 30

4. A machine for treating metal sheets comprising spaced pairs of feeding rolls and sheet stressing means disposed to operate in the space between said pairs of feeding rolls, said stressing means comprising at least two vertically deep rigid beams extending substantially from side to side of the machine and each carrying roller means for engagement with a sheet being treated, said roller means also extending substantially from side to side of the machine, and bearings on said beams for supporting said roller means at longitudinally closely spaced points along the beams, said roller means being of relatively small diameter as compared with the diameter of the feed rolls and arranged when in operative position in staggered relation transversely of the machine, whereby the sheet is given a plurality of sharp bends in its passage through the machine. 45

5. A sheet treating machine adapted to operate on wide sheets comprising spaced pairs of sheet feeding rolls and means for stressing the metal of the sheet in its passage through the space between said pairs of rolls, the said means comprising at least one series of rollers of small diameter as compared with the diameter of the feed rolls arranged transversely to the direction of travel of the sheet and a vertically deep rigid support for said rollers, the rollers being arranged in close proximity and individually rotatably mounted on independent bearings disposed between spaced narrow extensions of the support, each said extension being arranged between a pair of adjacent rollers and of a width less than the width of the rollers, whereby the rollers pre- 50

sent a substantially continuous cylindrical periphery or surface.

6. A machine for treating wide metal sheets comprising spaced pairs of feeding rolls and stressing means disposed to operate upon a sheet while passing between said pairs of feeding rolls, said stressing means comprising at least one series of rollers, and bearing blocks each having an extension narrower than the rollers extending between and supporting said rollers for individual rotation on independent bearings and in closely spaced relation to present a substantially continuous cylindrical periphery or surface, and a vertically deep rigid beam removably mounting said bearing blocks.

15. 7. A sheet treating machine adapted to operate on wide sheets comprising spaced pairs of

sheet feeding rolls and means for stressing the metal of the sheet in its passage through the space between said pairs of rolls, the said means comprising at least one series of slightly crowned rollers of small diameter as compared with the 5 diameter of the fed rolls arranged transversely to the direction of travel of the sheet and a vertically deep rigid support for said rollers, the rollers being arranged in close proximity and individually rotatably mounted on independent 10 bearings supported by narrow extensions on the support, said extensions being disposed between the rollers and being narrower than the rollers, whereby the rollers present a substantially continuous cylindrical periphery or surface. 15

ERIC BIRGER FERNBERG.
